ATOMIZER

Walter J. Mehrman and Clifford J. Mehrman,
Toledo, Ohio

Application February 20, 1936, Serial No. 64,942

1 Claim. (Cl. 299—88)

This invention relates to an atomizer.

It is aimed to provide an exceedingly simple and compact atomizer capable of manufacture at minimum cost and adapted for manufacture in attenuated form whereby it is well adapted to be carried in the pocket or in a lady's handbag like a pen or pencil.

Such an atomizer is particularly useful in spraying perfume, medical oils as for nasal, throat and ear infections, oils on to fishermen's flies or the like.

Various objects and advantages will become apparent from a consideration of the description following taken in connection with accompanying drawing illustrating an operative embodiment.

In said drawing:—

Figure 1 is a view in elevation of the improved atomizer;

Figure 2 is a longitudinal sectional view taken on the line 2—2 of Figure 1;

Figure 3 is a transverse sectional view taken on the line 3—3 of Figure 2; and

Figure 4 is a transverse sectional view taken on the line 4—4 of Figure 2.

Referring specifically to the drawing, wherein like reference characters designate like or similar parts, the atomizer has a cylinder 10 provided with an end wall 11 and with screw threads 12 at the opposite end detachably engaged by a tip or nozzle 13. Any suitable material to be sprayed or atomized is contained within the space or chamber of the barrel 10 and to be atomized or leave the same through an outlet tube 14, surrounding an air tube 15, with less diameter than the bore of the tube 14. The material and air admixing in a chamber 16 at the outer end portion of the nozzle 13 and leaving through an orifice 17.

Said air tube 15 is anchored in a nipple 18 extending from the wall 11 of the cylinder and removably secured about the nipple 18 by means of a nut 19, is a packing cup 20 of leather or the like and an expander 21 therefor. The wall 11 is extended outwardly as at 22, to co-act with the packing 21 to form a piston.

Said piston is located within the bore of a tubular plunger 23 and said packing 20 intimately engages the bore wall of such plunger. One end of the plunger has an inwardly extending flange 24 to overlap the projecting portion 22 to prevent accidental detachment of the plunger. An expansive coil spring 25 located within the plunger 23 engages the piston at one end and a closure 26 for the plunger at the other

end. Such closure is screw threaded in the plunger as at 27 and it has check valve 28 mounted in a cage 29, a passageway 30 through the closure establishing communication with the atmosphere under the control of such valve 28. 5

Such plunger is adapted to be pressed inwardly toward the piston wall 11 to eject air under pressure through the tube 15, chamber 16, where it admixes with the material to be atomized, passing to the tube 14, and thence being atomized 10 through the orifice 17. Such plunger is slidably accommodated between the cylinder 10 and the cylindrical or tubular sheath 31 fastened at an inwardly enlarged portion 32 to the cylinder. A vent passage 33 extends through the nozzle 13 15 from the exterior to the interior of the cylinder.

It is clear that the material in the cylinder 10 is atomized through rapid and repeated depressions of the plunger 23, causing air to pass through the tube 15 and the material to pass 20 through the tube 14, such air and materials admixing in chamber 16 and being ejected and atomized through the orifice 17.

Especially since the device is adapted to be carried in the pocket or a pocketbook, a cap 34 25 is provided which is detachably screw threaded as at 36 to the sheath 31. This cap contains a soft rubber or other gasket block 35 adapted for direct contact with the outer end of the nozzle 13 in order to close the orifice 17 against leakage. 30 In addition, a clip 36' is provided on the cap to facilitate attachment to the pocket or the equivalent and this clip has an anchor portion 37 extending through the wall of the cap and to the interior thereof and held in place by a ring 38 35 suitably secured interiorly of and to the cap.

Various changes may be resorted to provided they fall within the spirit and scope of the invention.

I claim as my invention:—

An atomizer of the class described having a cylinder, an end wall on said cylinder, an outwardly extending flange on the cylinder adjacent to said wall, a nozzle at the other end of the cylinder having an outlet orifice, an air tube communicating with the orifice and mounted by said wall, a tube communicating with the nozzle in communication with the orifice and adapted to convey material from the cylinder to be atomized, and a plunger surrounding and in telescopic 50 relation with the cylinder operable to force air through the tube first mentioned, an inwardly extending flange on the plunger adapted to abut the first mentioned flange to limit outward movement of the plunger, an expansive spring 55

urging the plunger in a direction away from the cylinder, a check valve in the end wall of the plunger, and the latter end wall having a passage opening at a side thereof establishing communication between the interior of the plunger and the atmosphere under control of the valve, said nozzle having a passage leading from the atmosphere to the interior of the cylinder, and a sheath

secured to the cylinder adjacent the nozzle and extending beyond the piston wall and in overlapping relation with the plunger, said sheath having an inward enlargement for abutment by the flange of the plunger to limit inward movement of the plunger. 5
